INVENTOR.

UNITED STATES PATENT OFFICE

153,420

DESIGN FOR A DESK CLOCK

Leon M. Dekanski, New York, N. Y.

Application November 12, 1947, Serial No. 142,463

Term of patent 7 years

(Cl. D42—7)

To all whom it may concern:

Be it known that Leon M. Dekanski, citizen of the United States, residing at 315 West 75th Street, New York, in the county of New York and State of New York, has invented a new, original, and ornamental Design for a Desk Clock, of which the following is a specification, reference being had to the accompanying drawing, forming part thereof, in which:

Fig. 1 is a plan view of desk clock, showing my new design.

Fig. 2 is a side view of the same.

I claim:

The ornamental design for a desk clock, substantially as shown.

LEON M. DEKANSKI.
